TORPEDO PROPELLING AND STEERING
MEANS

Christ T. Petkoff, Kansas City, Mo.

Application April 15, 1942 Serial No. 439,001

8 Claims. (Cl. 114—19)

My invention relates to improvements in torpedo propelling and steering means.

One of the objects of my invention is the provision of novel means by which a self propelled torpedo of usual type can be propelled and steered by a power propelled boat, and, when arriving at a desired location, released by operator controlled means on the boat, and permitted to continue its course to its objective under its own power.

A further object of my invention is the provision of novel supplemental means by which the propelling boat can push and steer the torpedo after the locking means connecting the boat and torpedo has been released, and which automatically releases when the torpedo proceeds under its own power.

Still another object of my invention, is the provision of novel propelling and steering means of the kind described, which is simple, strong, durable, not likely to get out of order, which is easily operated to propel and steer the torpedo, and which is efficient in its operation.

The novel features of my invention are herein-after fully described and claimed.

In the accompanying drawing, which illustrates a preferred embodiment of my invention,

Fig. 1 is a side elevation, partly broken away, showing the torpedo operatively locked to the propelling boat.

Fig. 2 is a top view of the torpedo and boat operatively connected.

Fig. 3 is a section on the line 3—3 of Fig. 1, enlarged and broken away, showing the connecting bars locked together.

Fig. 4 is front end elevation of the propelling boat, partly broken away and enlarged, showing the locking means in the release position.

Fig. 5 is an enlarged view looking forwardly from the inside, showing a portion of the propelling boat, and showing the locking operating shaft, its operating lever and the arcuate bar which locks the lever in its two positions, shown respectively in solid and dotted lines.

Fig. 6 is an enlarged longitudinal sectional view of the rear end portion of the torpedo, and a front end portion of the supplemental pushing and steering bar operatively engaged with the torpedo, parts of the torpedo being omitted.

Fig. 7 is an enlarged top view of portions of two of the aligned pushing bars lockingly engaged with each other by one of the locking arms.

Fig. 8 is an enlarged view, partly in side elevation and partly in vertical section, showing one

of the push bars of the boat fastened to the boat, parts being omitted.

Fig. 9 is a reduced top view of a front end portion of the propelling boat, and the axial oscillating locking shaft and the radial arm carried by the shaft and having the locking fingers.

Similar characters of reference designate similar parts in the different figures.

1 designates the hull of a usual self propelled 10 torpedo. 2 designates the hull of a power propelled boat, such as a small submersible, designed to propel and steer the torpedo 1 to a desired location, where the torpedo is to be released and then to be propelled by its own power to its objective, as a boat to be torpedoed.

On the top of the boat hull 2 is provided with the usual conning tower 3, having the usual conning port 4, and having projecting upwardly from the conning tower, the usual periscope, 5. 6 designates the usual propeller and 7 the usual rudder.

Pushing and steering means are provided for connecting the torpedo 1 releasably to the boat 2 in front thereof. Such means in the form shown, comprise the following described parts.

Three longitudinal rigid bars 8 are fastened at their front ends at spaced apart intervals around the periphery of the torpedo 1 and extend rearwardly therefrom.

30 Three longitudinal bars 9 respectively substantially aligned with the bars 8 have their rear ends fastened to and extending forwardly from the hull 2 of the boat. The bars 8 and 9 of each aligned pairs are respectively provided with transverse perforations or holes 10 adapted to register, and when so registering, to receive therethrough locking means, which, as shown, consists of a locking finger 11, provided with means for oscillating it to and from the locking position, shown in Figs. 1, 2, 3 and 7.

As shown in Figs. 1 to 4, the fingers 11 are mounted rigidly on the outer periphery of a rigid arcuate transverse bar 12 fastened to the outer end of a radial arm 13 on the front end of a longitudinal axial oscillating operating shaft 14, which extends rearwardly from in front of the hull 2 to a vertical plane at the front of the conning tower 3, see Figs. 1 and 5.

In the cabin 15 of the boat, the rear end of the operating shaft 14 has fastened to it an operating lever 16, which swings at the rear of an arcuate bar 17, fastened to the front wall 18 of the cabin 15, as shown in Figs. 1 and 5. The rear side of the arcuate bar 17 is provided with two spaced apart notches 19 and 20. The lever

16 is sufficiently resilient to be swung rearwardly out of the notches 19 and 20, when it is designed to swing the lever to oscillate it and the shaft 14 from one position to the other. When the lever 16 is in the notch 19, as shown in solid lines in Fig. 5, it is the locking position, in which position, the shaft 14 holds the radial arm 13, in the position shown in Fig. 3, in which the fingers 11 respectively extend through the holes 10 in the pairs of pushing bars 8 and 9 and lock the bars of aligned pairs to each other, as shown in Figs. 1, 2 and 3.

As shown in the drawing, the front ends of the bars 9 are forked, and the rear ends of the bars 8 extend respectively between the arms of such forked ends.

For bracing the bars 9 to each other, there is provided an arcuate transverse bar 21, the inner side of which is rigidly secured to the outer sides of the bars 9 adjacent to their forward ends, as shown in Figs. 1 to 4.

For serving the double purpose of stiffening the connection between the torpedo and the boat hull, and of serving to push the torpedo 1 after the locking means, already described, has been released, there is provided a longitudinal rigid bar 22, the rear end of which is fastened to the under side of the front end portion of the hull 1, and extends forwardly therefrom into a longitudinal hole 23 provided in the rear end portion 30 of the torpedo 1, as shown in Figs. 1 and 6.

For preventing the bars 8 and 9 from lateral movement at their attached ends to the torpedo and boat respectively, they have such attached ends disposed in longitudinal grooves respectively in the torpedo body and hull 2 of the boat, such groove 24 being shown in Fig. 8, in which the rear end of the bar 9 is disposed and fastened by a bolt 25.

The bars being locked together, as shown in Figs. 1, 2 and 3, by the fingers 11 of the locking mechanism, the boat controlled by the operator of the boat, propels the torpedo 1 to the location where it is desired to release it for it to effect its function. When the torpedo has been so propelled and steered by the propelling boat 2, and has been directed to its objective, the operator on the boat releases the lever 16 from the notch 19, and swings the lever to the release position, clockwise, as viewed in Fig. 5, to the dotted position in Fig. 5, and then permits the lever to enter by its tension the notch 20, in which position it is locked by the bar 17. The shaft 14 will have been turned to the release position, thus turning the radial arm 13 to the release position shown in Fig. 4, in which position the fingers 11 will have been withdrawn from locked engagement with the bars 8 and 9.

The supplemental pushing bar 22 is still engaged with the torpedo, so as to push it forward, until by its own power it is propelled forwardly, at which time, the supplemental pushing bar 22 is withdrawn from the hole 23, and the torpedo is propelled by its own power, a rear propeller 26, Fig. 1, to its objective.

The operator of the propelling boat 1, can then submerge, if he so desires, or turn away and seek safe quarters.

When the push bars 8 are coupled to the push bars 9, as has been described, the torpedo is disposed already launched in the water in front of the boat 2 and headed in the same direction, in fixed launched relation thereto, so its is but required to face the boat toward the objective and

release the coupling to have the torpedo proceed under its own power.

With my invention, a small submarine, operated by one person can propel and steer a torpedo, unobserved, to close striking distance from an objective, as a battle ship or other vessel, then release the torpedo to have it continue its course to the objective, and then, due to its small size, turn away, submerged if in daylight, or on the surface, if at night and proceed from any dangerous location near the objective, if such be a warship.

My invention is not confined to any species of torpedoes, or of propelling and steering boats therefor, as many types of such may be employed with advantage in the use of my invention. Nor do I confine my invention to the specific structure shown and described, as one form of my invention, as many modifications thereof, within the scope of the appended claims, may be made without departing from the spirit of my invention.

What I claim is:

1. In a torpedo propelling and steering means, in combination, a self propelled torpedo, a boat having power operated propelling means, two longitudinal bars, one fastened to and extending rearwardly from said torpedo, the other bar being fastened to and extending forwardly from said boat, the torpedo being disposed launched in the water in front of said boat, and headed in the same direction and means, releasable by an operator on said boat, coupling together said bars and holding said torpedo in fixed launched relation to said boat.

2. In a torpedo propelling and steering means, in combination, a self propelled torpedo, a boat having power operated propelling means, a plurality of longitudinal bars fastened to and extending rearwardly from and spaced apart around the periphery of the torpedo, a plurality of longitudinal bars fastened to and extending forwardly from and spaced apart around the periphery of said boat, the torpedo being disposed launched in the water in front of said boat and headed in the same direction, and means, releasable by an operator on said boat, coupling said first named bars respectively to said second named bars and holding said torpedo in fixed launched relation to said boat.

3. In a torpedo propelling and steering means, in combination, a self propelled torpedo, a boat at the rear thereof headed in the same direction and having power operated propelling means, a longitudinal bar fastened to and extending rearwardly from the torpedo and having a transverse perforation, said torpedo being launched in the water; a longitudinal bar fastened to and extending forwardly from said boat and having a transverse perforation aligned with said first named perforation, a locking member extending removably through said perforations for holding together said bars and holding said torpedo in fixed launched relation to said boat, and means on said boat for withdrawing said locking member from at least one of said perforations to release said bars from each other.

4. In a torpedo propelling and steering means, in combination, a self propelled torpedo, a boat at the rear thereof having power operated propelling means, a longitudinal pushing member fastened to and extending rearwardly from the torpedo which is launched in the water and headed in the same direction as said boat, pushing means on said boat, releasable locking means

connecting said pushing member with said pushing means and holding said torpedo in fixed launched relation to said boat, and means on said boat for operating said locking means to release said pushing member from said pushing means.

5. In a torpedo propelling and steering means, in combination, a self propelled torpedo, a boat at the rear thereof having power operated propelling means, two longitudinal bars fastened peripherally spaced apart to and extending rearwardly from the torpedo, two longitudinal bars in substantial alinement with said two bars and fastened to and extending forwardly from said boat, an oscillative member on said boat extending forwardly therefrom, and means locking together respectively said first named bars and said second named bars and actuated by said oscillative member when it is swung in one direction for simultaneously releasing the first named bars from the last named bars.

6. In a torpedo propelling and steering means, in combination, a self propelled torpedo, a boat at the rear thereof having power operated propelling means, spaced apart longitudinal bars fastened to the periphery of and extending rearwardly from the torpedo, spaced apart bars fastened to and extending forwardly from said boat respectively in substantial alinement with said first named bars, a longitudinal shaft oscillative on its axis and extending forwardly from said boat, and means actuated by said shaft when the latter is turned to one position for locking said first named bars to said second named bars respectively and which locking means releases said

bars from each other when said shaft is turned from said position.

7. In a torpedo propelling and steering means, in combination, a self propelled torpedo, a boat at the rear thereof having power operated propelling means, spaced apart longitudinal bars fastened to and extending rearwardly from the torpedo, spaced apart bars fastened to and extending forwardly from said boat substantially alined with said first named bars, each pair of said alined bars having transverse holes adapted to register with each other, a longitudinal shaft oscillative on its axis on and extending forwardly from said boat, and locking means on and oscillative with said shaft and adapted to be extended through said holes for locking together the alined ones of said bars when said shaft is turned in one direction to one position, and withdrawn from said holes and releasing said alined bars from each other when said shaft is turned in the opposite direction from said position.

8. In a torpedo propelling and steering means, in combination, a power propelled boat, a push bar fastened to and extending longitudinally forwardly therefrom, and a self propelled torpedo disposed launched in the water in front of said boat and headed in the same direction and having a longitudinal rearwardly facing hole closed at its front end, said push bar being removably slidably fitted in said hole and abutting at its front end against the closed end of said hole and by which said boat can push and steer said torpedo and be automatically released therefrom.

CHRIST T. PETKOFF.
